UNITED STATES PATENT OFFICE.

JAMES WEST, OF CHICAGO, ILLINOIS, ASSIGNOR TO BARNHART BROS. & SPINDLER, OF SAME PLACE.

DESIGN FOR A FONT OF PRINTING-TYPE.

SPECIFICATION forming part of Design No. 23,107, dated March 6, 1894.

Application filed December 21, 1893. Serial No. 494,353. Term of patent 14 years.

To all whom it may concern:

Be it known that I, JAMES WEST, a citizen of the United States, residing at Chicago, county of Cook, and State of Illinois, have invented and produced a certain new and original Design for a Font of Script Type, which is fully set forth in the following specification, reference being had to the accompanying drawing, forming a part thereof.

This design comprises upper case and lower case letters, figures, points, dollar mark and character &. The general character of the design is a hair-line-and-shade upright script without marked peculiarities in the lower case letters, but having all the upper case letters, with two exceptions, characterized by a hair line curve flourish extending obliquely below the line, such hair line connecting with the top of stem of letters which have a stem, and originating or merging in a loop at the upper part of the letters which are without stems. Of the first class, B, F, H, K, L, P, and T are instances. Of the second, A, C, D, E, G, I, M, N, O, S, U, V, W, X, Y and Z are instances. Capital J, of the conventional form having the loop below the line, lacks this hair-line flourish, but in lieu of it has a hair line of the loop extended across the stem, and in the case of capital Q, the hair line is looped within the oval of the letter and has the characteristic of the letter annexed to its lower end below the line, the loop taking up a part of the length of the hair line, so that it does not terminate so far below the line as in the case of the other letters. These two letters J and Q are therefore not entirely exceptions to the rule as to the presence of the hair line flourish, but it is so far modified in them as to make them exceptional.

Special peculiarities of the different letters, 40 consistent with the general characteristics of the entire font, and tending to give the whole font, especially as to capitals, a graceful ornamental appearance, may be noted:—A small loop, not necessarily pertaining to the conventional outline of the letter, is incorporated in the upper element or part of many letters, usually following the hair line flourish. Instances of this are seen in capitals C, D, E, G, and S. Quite similar to this feature,—being, 50 in fact, the same feature modified only by the conventional outlines of the letters,—is the feature found in letters whose conventional form contains such a loop, the hair line merging in the loop. Instances of this are capitals 55 I, M, N, U, V, W, X, Y and Z. A further adaptation of the same characteristic to the conventional form of the letter when that form is the general oval is seen in capitals A and O. The general style of the lower case letters, 60 figures and points harmonizes with the capitals, but without special individual characteristics in the different letters or characters.

I claim—

The design for a font of script type herein 65 shown and described.

In testimony whereof I have hereunto set my hand at Chicago, Illinois, this 16th day of December, 1893.

JAMES WEST.
